UNITED STATES PATENT OFFICE.

CARL V. HELMSCHMIED, OF MERIDEN, CONNECTICUT.

DESIGN FOR A TOP FOR PEPPER OR SALT BOTTLES.

SPECIFICATION forming part of Design No. 37,243, dated November 22, 1904.

Application filed April 9, 1903. Serial No. 151,935. Term of patent 3½ years.

To all whom it may concern:

Be it known that I, CARL V. HELMSCHMIED, a citizen of the United States, residing at Meriden, in the county of New Haven and State of Connecticut, have invented a new, original, and ornamental Design for a Top for Pepper or Salt Bottles, of which the following is a specification, reference being had to the accompanying drawing, forming part thereof.

10 The figure is a side elevation of my invention.

What I claim as new, and desire to secure by Letters Patent, is—

The ornamental design for a top of a pepper or salt bottle, as shown.

CARL V. HELMSCHMIED.
